SEPARABLE BASE AND CAP GAS BURNER

Herbert M. Reeves, Kankakee, Ill., assignor to
Florence Stove Company, Gardner, Mass., a
corporation of Massachusetts

Application March 1, 1946, Serial No. 651,101

5 Claims. (Cl. 158—116)

1

The invention relates to gas burners and more particularly to burners of the type having separable base and head elements.

Burners of the above general character are commonly constructed with a cup-shaped base usually in the form of a casting. A separately formed head mounted within the base is provided with a radially projecting portion adapted to extend over and cooperate with the side walls of the base to define the outlet ports for the burner. In order to provide ports of sufficient length to prevent backfiring, it is customary to form the side walls of the base with an overhanging inwardly projecting flange or lip of substantial width. The formation of this lip introduces substantial difficulties in the casting of the burner bases and materially increases their cost.

One object of the invention is to improve the construction of burners of the above general character so as to eliminate the foregoing difficulties and to provide a burner which is simple and inexpensive to manufacture, efficient and reliable in operation, attractive in appearance, and easy to keep clean.

A more specific object is to provide a burner construction which enables the burner base to be formed with substantially straight side walls with a consequent reduction in the cost of production of the same.

Still another object is to provide a gas burner construction which materially simplifies the finishing of the cast parts of the burner.

A further object is to provide an improved arrangement for supporting a lighter tube on the burner which effectually prevents clogging of the tube or the lighter port by the accumulation of dirt and grease and which materially increases the life of the tube and associated parts.

Other objects and advantages of the invention will become apparent from the following detailed description of the preferred embodiment of the invention shown in the accompanying drawing in which:

Figure 1 is a vertical sectional view of a gas burner embodying the features of the invention.

Fig. 2 is an exploded view showing the relationship between the burner head, the auxiliary port forming member and the lighter tube.

Fig. 3 is an enlarged fragmentary sectional view showing the manner in which the burner base and head coact to form the outlet ports for the burner.

Fig. 4 is a sectional view taken in a plane substantially on the line 4—4 of Fig. 3.

While the invention is susceptible of various

modifications and alternative constructions, I have shown in the drawing and will herein describe in detail the preferred embodiment, but it is to be understood that I do not thereby intend to limit the invention to the specific form disclosed, but intend to cover all modifications and alternative constructions falling within the spirit and scope of the invention as expressed in the appended claims.

Referring to the drawing, the gas burner selected to illustrate the invention comprises a generally cup-shaped base 5 including an upstanding annular side wall 6 and a centrally apertured bottom wall 7. A mixture of gaseous fuel and primary air is supplied to the burner base through a mixing tube 8 arranged to communicate with the interior of the base. In practice the base 5 and mixing tube 8 are commonly formed as an integral casting.

Assembled with the base 5 is a mushroom-shaped head 9 which cooperates therewith to form an annular distribution chamber 10 with a plurality of outlet ports 11 around its outer peripheral edge. The head 9 is formed with a cylindrical stem portion 12 and a radially outwardly and upwardly projecting flange portion 13 dimensioned to extend over the side wall 6 of the base. As herein shown, the stem 12 and the aperture in the wall 7 of the base are threaded for interfitting engagement. The stem is preferably of tubular form and provides a passage for supplying secondary air to the inner side of the flame ring formed by the ports 11.

In the exemplary burner the marginal edge portion of the flange 13 is finished on its underside to provide an upwardly and outwardly inclined or generally frusto-conical area of substantial width measured radially of the flange. A series of downwardly opening radially disposed grooves 14 in the frusto-conical area of the flange serve to define the outlet ports 11 for the burner as will appear presently. As shown in Fig. 3 the grooves 14 are of substantial length and are preferably generally semi-cylindrical in cross section.

In order to simplify the construction of the base 5 and thus facilitate its production as a casting I provide an auxiliary port forming member 15 adapted to be interposed between the side wall 6 of the base and the flange 13 of the head to define therewith the outlet ports 11 for the burner. The auxiliary member 15 comprises a relatively thin annulus preferably constructed of sheet metal and including a frusto-conical port forming element 16 adapted to overlie the side wall 6.

of the base substantially transversely thereof. The upper edge of the wall 6 is beveled as at 17 to provide a firm seat for the port forming element of the member.

When the burner is assembled the flange 13 of the head engages the port forming element 16 of the auxiliary member and clamps it against the beveled edge 17 of the side wall 6. The element 16 of the auxiliary member thus closes the lower sides of the grooves 14 in the flange to define therewith the elongated outlet ports 11 for the burner. It will be evident that with this construction the length of the ports is determined by the width of the grooved area of the flange 13 and the width of the port forming element 16 independently of the thickness of the wall 6 of the burner base. Accordingly, the latter may be formed as a relatively thin substantially straight annular wall which can be produced easily and economically as a casting. In particular the absence of an internal flange on the wall of the burner base is advantageous from the production standpoint.

The auxiliary member 15 may also be utilized to substantially enclose the burned base 5 and thus make it unnecessary to provide the base with a fine finish. To this end, the port forming element 16 of the member is merged into a depending skirt portion 18 adapted to encircle and conceal the side wall 6 of the base.

Provision is made for accurately centering the auxiliary member 15 on the burner base to insure uniformity in the length of the ports 11. For this purpose the side wall 6 of the base is formed with radially outwardly projecting locating means 20 engageable by the skirt portion 18 of the auxiliary member to locate the same with respect to the base. The locating means 20 may be in the form of a continuous rib around the wall 6 or may comprise a plurality of spaced lugs arranged circumferentially of the wall. Thus in assembling the burner it is only necessary to slip the auxiliary member over the burner base and to screw the head 9 in place therein.

To facilitate cleaning of the burner and to give it a neat, attractive appearance, the outer surface of the auxiliary member 15 and the upper surface of the head 9 may be finished with coating 21 and 21a of vitreous enamel. As the skirt portion 18 of the member extends around and substantially conceals the side wall of the burner body 5 the need for attractively finishing the latter is avoided. Thus the difficulty and expense of enameling the irregularly shaped base casting is eliminated.

Means is provided on the auxiliary member for supporting a lighter tube 23 in a manner such as to minimize the accumulation of dirt or grease at the junction between the tube and the burner. To this end the lower edge of the skirt portion 18 of the member is formed with a pair of tabs 24 adapted to be bent back on the member to form hook-shaped supports. The tabs 24 are spaced apart to receive a pair of outwardly bent ears 25 formed on opposite sides of the lighter tube 23. A notch 26 in the skirt 18 intermediate the supporting elements 24 and a lighter port 27 in the wall 6 of the base aligned with the notch 26 provide a passage for the gas issuing from the lighter port when the burner is turned on. Due to the relatively small area presented by the supports 24 and ears 25, the tendency for dirt and grease to collect around the lighter port is minimized. Clogging of the lighter port and tube is thus effectively prevented and damage to the tube

through the burning of such accumulated materials is eliminated with a corresponding increase in the useful life of the tube.

The improved burner may be constructed to provide an inner flame ring if desired by providing suitable ports 30 in the flange 13 of the head communicating with the annular distribution chamber 10. These ports are preferably formed intermediate the stem 12 and the marginal edge portion of the flange. As shown in Fig. 1 the ports are preferably inclined so as to produce an inwardly and upwardly directed flame.

It will be apparent from the foregoing that the invention provides a gas burner of novel and advantageous construction which is simple and inexpensive to manufacture, attractive in appearance and efficient and reliable in operation. The provision of an auxiliary member adapted to be interposed between the burner base and the head and cooperating with the head in forming the main outlet ports for the burner provides ports of sufficient length to effectually prevent backfiring and at the same time permits the base to be constructed with straight side walls. Thus manufacture of the burner base is simplified without sacrificing burner efficiency. The use of the auxiliary member is also advantageous in that it is easily finished in an attractive manner and eliminates the need for finishing the cast base portion of the burner. Furthermore the auxiliary member may be conveniently arranged for supporting the lighter tube in a manner such as to minimize the accumulation of dirt and grease around the burner.

I claim as my invention:

1. In a gas burner, in combination, a burner base including a bottom wall and an upright annular side wall, a head mounted on said base substantially centrally of said side wall and having a radially projecting flange portion extending above the side wall, a sheet metal member having an inwardly and downwardly projecting port forming portion interposed between the top of said side wall and the flange portion of said head, said flange being formed on its underside with radially disposed grooves cooperating with the port forming portion of said member to define outlet ports for the burner, a depending skirt portion integral with said port forming portion of the member encircling said side wall, and a pair of hook-shaped lugs spaced apart circumferentially of said skirt portion of the member and projecting radially therefrom for supporting a lighter tube, said skirt portion and said wall being apertured to provide a gas discharge port between said lugs.

2. In a gas burner, in combination, a burner base including an upright annular side wall and a bottom wall, said side wall having a radially opening lighter port, a head having a stem supported on the bottom wall substantially centrally of the side wall and a radially projecting flange portion extending above the wall, a sheet metal member including a depending skirt portion encircling said side wall and an inwardly and downwardly inclined flange portion overlying the upper edge of said side wall, one of said flange portions being formed with radially disposed grooves cooperating with the other flange portion to form outlet ports for the burner, a lighter tube having a pair of laterally bent ears at one end, and a pair of radially projecting lugs on said skirt portion spaced apart to receive said ears and thereby support the lighter tube, said lugs

being located on opposite sides of the lighter port in said wall and said skirt portion having an opening between the lugs to provide a passage for the gas issuing from the lighter port.

3. A gas burner comprising, in combination, a burner base including an upright side wall and a bottom wall, a burner head having a central stem portion adapted to be secured to said bottom wall and cooperating with the base to form an annular fuel distribution chamber, a flange adjacent the upper end of said stem projecting radially outwardly to overlie the upper edge of said side wall and acting to close the upper end of said chamber, said flange having the underside of its marginal edge portion formed with radially disposed grooves, and a sheet metal member having an annular portion interposed between the upper edge of said side wall and the grooved portion of said flange to define therewith a series of burner ports opening from said chamber, said annular portion of the member having a width materially greater than the thickness of said side wall so as to make the burner ports substantially longer than the thickness of said side wall.

4. A gas burner comprising, in combination, a burner base including an upright side wall and a bottom wall, a burner head having a central stem portion adapted to be secured to said bottom wall and cooperating with the base to form an annular fuel distribution chamber, a flange adjacent the upper end of said stem projecting radially outwardly to overlie the upper edge of said side wall and acting to close the upper end of said chamber, a sheet metal member having an annular portion interposed between and coacting with the upper edge of said side wall and the overlying portion of said flange, one of said coacting parts being formed with radially disposed grooves to provide a series of burner ports opening from said chamber, said annular por-

tion of the member having a width materially greater than the thickness of said side wall so as to make said burner ports substantially longer than the thickness of said side wall.

5. A gas burner comprising, in combination, a burner base including an upright side wall and a bottom wall, a burner head having a central stem portion adapted to be secured to said bottom wall and cooperating with the base to form an annular fuel distribution chamber, a flange adjacent the upper end of said stem projecting radially outwardly to overlie the upper edge of said side wall and acting to close the upper end of said chamber, a sheet metal member having an annular portion interposed between and coacting with the upper edge of said side wall and the overlying portion of said flange, one of said coacting parts being formed with radially disposed grooves to provide a series of burner ports opening from said chamber and said annular portion of the member being of a width such as to make said ports substantially longer than the thickness of said side wall, a skirt portion depending from the outer edge of the annular portion of said member, and means on said side wall coacting with said skirt portion to center the member with respect to the burner base.
